UNITED STATES PATENT OFFICE

164,576

TIME CONTROLLED PET FEEDER

Fred A. Hedwall, Sacramento, Calif.

Application March 28, 1950, Serial No. 8,822

Term of patent 3½ years

(Cl. D12—2)

To all whom it may concern:

Be it known that I, Fred A. Hedwall, a citizen of the United States, residing at Sacramento, in the county of Sacramento and State of California, have invented a new, original, and ornamental Design for a Time Controlled Pet Feeder, of which the following is a specification, reference being had to the accompanying drawing, forming part thereof.

Fig. 1 is a frontal perspective view of a time controlled pet feeder showing my new design;

Fig. 2 is a top perspective view;

Fig. 3 is a side perspective view, both sides being identical; and

Fig. 4 is a rear perspective view of my new design.

I claim:

The ornamental design for a time controlled pet feeder, as shown and described.

FRED A. HEDWALL.
